[57] CLAIM

The ornamental design for a reenforced storage tank,
as shown and described.

DESCRIPTION

FIG. 1 is a perspective view of a reenforced storage tank showing our new new design;

FIG. 2 is an elevational view taken from one end thereof, the opposite end being the same as the end shown;

FIG. 3 is an elevational view taken from one side thereof, the opposite side being the same as the side shown;

FIG. 4 is a top plan view thereof;

FIG. 5 is a cross sectional view taken on line 5—5 of FIG. 3; and

FIG. 6 is a cross sectional view taken on line 6—6 of FIG. 2.

FIG. 1**FIG. 2****FIG. 3****FIG. 4****FIG. 5****FIG. 6**
